UNITED STATES PATENT OFFICE.

GEORGE A. BOWMAN AND CYRUS L. HARMEYER, OF FORT WAYNE, INDIANA.

BRAKE-HEAD.

1,176,129.

Specification of Letters Patent. Patented Mar. 21, 1916.

Application filed July 22, 1915. Serial No. 41,237.

To all whom it may concern:

Be it known that we, GEORGE A. BOWMAN and CYRUS L. HARMEYER, citizens of the United States, residing at Fort Wayne, in 5 the county of Allen and State of Indiana, have invented a certain new and useful Improvement in Brake-Heads, of which the following is a description.

The invention relates to new and useful 10 improvements in brake-heads, and particularly to an improvement upon the brake head described in our former Patent No. 901,872, granted October 20, 1908. In the latter patent we describe a head consisting 15 of a thrust block adapted to be secured to a brake beam. The brake head is divisible so that if one head member becomes worn the worn part only is removed and replaced by a duplicate. 20 The two head members are each provided with a tenon which is insertible in an opening or recess provided in the thrust block, and are removably secured to the block by a pin which is passed through a vertical opening 25 in the block and through openings in the tenons. The assembled device is supported from the vehicle by a hanger which is engaged in a slot or recess provided in the forward face of the block and between 30 the adjacent ends of the heads. The shoe prevents the disengagement of the hanger from the block. The disadvantage of this method of support for the device is that there is no means provided on the thrust 35 block to prevent the disengagement of the hanger from the block when the shoe is removed or drops off the head members or when the upper member of the head is removed. In substituting a new shoe or head 40 member or in case of the loss of a shoe it is desirable that the thrust block shall remain in position—that the beam and block shall not fall down and thereby endanger the train or delay the repair of the device. 45 The object of our invention is to provide a novel means for connecting the thrust block to the hanger to insure their unauthorized separation.

In the drawings we illustrate the preferred manner of carrying out our invention in which—

Figure 1 is a side elevational view of the assembled device attached to the hanger according to our invention; Fig. 2 a front elevational view of the same, the upper head

member being removed; Fig. 3 a vertical section on line 3—3 of Fig. 1 and Fig. 4 a side elevational view of one of the head members.

Referring to the drawings the rear portion of thrust block 10 is apertured in any desired form, as aperture 11, so that it may be engaged on the end of the brake beam. Two suitably spaced apertures or recesses 12 are provided in the front portion of the 60 block, the apertures opening at the forward face of the block. A slot or recess 13 is also provided in the block preferably above apertures 12 and extends transversely entirely across the block for the reception of 70 hanger 14. A vertical opening or key way 15 intersects the hanger slot and both apertures 12. Two brake head members 16, having tenons 17 projecting from their rear faces and apertured bosses 18 projecting from 75 their opposite faces are adapted to be secured to the block, the tenons being inserted in apertures 12. The apertured bosses 18 serve as means for securing the usual shoe to the head members by a key. Each tenon 80 has a vertical opening 19 which, when the tenons are properly inserted in recesses or apertures 12 will register with each other and with key way 15. The heads 16 being assembled on the block, and hanger 14 being 85 inserted into slot 13 and beyond key way 15, pin 20 is inserted into key way 15 and passed through slot 13 in front of the hanger and through the apertures in the tenons. The pin, therefore, not only secures 90 the brake head members to the block but also retains the hanger within the slot in the block. The pin need not be removed to replace a shoe, and to remove a worn out head member and substitute a new one the 95 pin need only be elevated sufficiently to release the tenon of the head member to be removed. The thrust block is, therefore, at all times suspended from the vehicle, provided of course, the hanger itself remains 100 uninjured.

What we claim is:

1. The combination with a thrust block having two recesses therein, a slot extending laterally through the block, a key way intersecting the slot and both recesses, a divisible brake head having apertures therein and within the recesses and in alinement with the key way, a hanger in the slot and a key extending through the key way and through 110

the alining apertures in the brake head and extending across the slot in front of the hanger.

2. The combination with a thrust block for attachment to a brake beam, having a plurality of transversely arranged recesses, a slot extending transversely of the same and the block having a vertically arranged key way therein which intersects each of

the recesses and the slot, a hanger in the slot, two brake head members having apertured tenons projecting into the recesses and a key extending across the slot in front of the hanger.

In witness whereof we hereunto subscribe our names this 15th day of July, 1915.

GEORGE A. BOWMAN.
CYRUS L. HARMEYER.
